MACHINE FOR THE PRODUCTION OF
KNITTED FABRICS

John Archibald Phillips, Nottingham, England

Original application May 3, 1930, Serial No. 449,646; now Patent No. 1,910,932, dated May 23, 1933. Divided and this application July 13, 1931, Serial No. 550,573. In Great Britain May 7, 1929

7 Claims. (Cl. 66—25)

This invention comprises improvements in machines for the production of knitted fabrics and has reference to machines of the type wherein rib knitted fabrics are produced by the employment of two sets or rows of needles operating to draw thread loops in opposite directions.

The invention that is covered by this case is a division of an application filed by the applicant on the 3rd May 1930 under Serial No. 449,646, Patent No. 1,910,932.

The main object of the present invention is to produce on a machine of the said type a rib knitted fabric wherein the ribs of one face are comprised of knitted loops of ground and plating threads, and the ribs of the other face are comprised solely of knitted loops of the ground thread about which latter loops the plating thread is looped without being knitted.

The said fabric may be of the single web type or may be comprised of two ribbed webs having crossed sinker wales, the ribs of one web being disposed in the spaces between the ribs of the other web.

According to the present invention a knitting machine is provided comprising two sets or rows of needles, means for operating said needles to draw their loops in opposite directions to produce rib fabric, thread feeding means for feeding ground and plating threads to said needles, means for operating the needles of one set to knit the ground thread and plating thread and the needles of the other set to knit only the said ground thread, said latter needles receiving the said plating thread and casting off same with the old loops on such needles which appertain to the last preceding course.

It is to be clearly understood that the invention may be applied to a circular machine or a flat or straight bar machine of any type.

For the purpose of more fully describing the nature of this invention, reference will now be made to the accompanying drawings, wherein:

Figures 1 and 2 are a front and plan respectively of an arrangement of needles and thread feeds according to the present invention.

Figures 3 and 4 are similar views of an alternative arrangement to that shown in Figures 1 and 2.

Figures 5 and 6 are views, in elevation and in plan, respectively, showing the manner in which the guard retains yarn on the needles.

The production of the improved single web plated ribbed fabric described and claimed in my concurrent application for patent referred to

above, may be carried out on a circular knitting machine of the customary type adapted for producing ordinary ribbed fabric, such a machine being provided with a set of vertically disposed cylinder needles arranged in a predetermined order and co-operating with a predetermined arrangement of horizontally disposed needles accommodated within radial tricks in a dial suitably supported concentric with the needle cylinder. The needles may conveniently be of the latch type and are slidably operated in the well known manner by means of cams rotating relatively to the said needle cylinder and dial.

In a machine as above adapted for the production of the said fabric there is one horizontal dial needle interposed between each pair of vertical cylinder needles around the machine, the rib loops being produced by the cylinder needles and the wale loops by the dial needles.

In one convenient arrangement of needles and thread feeding devices shown in Figures 1 and 2 the cylinder needles are designated 1 and the dial needles are designated 2.

The body or ground thread *g* and the plating yarn *p* are independently fed through suitable guides 3 and 4, at spaced positions around the machine and any suitable known type of thread tensioning devices may, if desired, be employed in connection therewith.

The sequential operation of the two sets of needles and the feeding of the threads in the production of the fabric are as follows:

The cylinder needles 1 rise as shown at *c* Figure 1 and clear their old loops beneath their latches and are then lowered to the tucking height at *D*.

Simultaneously, the dial needles 2 move forward under the influence of suitable cams of the customary type until they occupy the tucking position shown at *E*, Figure 2, the old loops thereon remaining over their latches as shown. The dial needles are then retracted, take the plating yarn *p* and draw said plating yarn over and between the cylinder needles at the position *F*, Figure 2. The needles 2 then again move forward and clear their old loops and the new plating yarn *p* beneath their latches at the position *G*, after which the dial needles are again retracted and the cylinder needles lowered to cause both sets of needles to take and knit the body or ground yarn *g* which is fed by the suitably positioned feeders 3.

Both sets of needles travel around the machine in the direction of the arrow *X*.

The thread *p* is plated over the thread *g* in the well known manner on the cylinder needles.

and covers the whole of the rib loops in the fabric, and the said yarn *p* is cast off with and covers the upper parts of the old wale loops or wale loops of the last preceding course formed 5 on the dial needles, and the said plated thread after leaving the dial needles appears on the same face of the fabric as the plated rib loops formed on the cylinder needles.

The loops of the plating thread *p* which rest 10 loosely on the dial needles 2, when they move forward for the second time at the position *G* to clear their old loops and the said plating thread beneath their latches, are retained on the needles, during such movement, by means of 15 a smooth wire or other resilient metal guard or keeper 5 which bears against the said loose plating yarn and, as shown, extends around part of the circumference of the machine, immediately at the rear of the cylinder needles 1 and beneath 20 the dial needles 2, the said keeper being supported from the dial cam box 6 or other convenient part of the machine.

The above sequence of operations may be repeated at one or more different positions around 25 the machine and any suitable known types of yarn changing mechanism may be employed at the positions where the ground and/or plating yarns are fed.

In the modified arrangement of needles and 30 yarn feeding device shown in Figures 3 and 4, the ground and plating yarns *g* and *p* are fed to the needles 1 and 2 through apertures 7 and 8 provided in a single feeder member 9 of any suitable form. The cylinder needles are raised 35 at the position *C*¹ in Figure 3 to clear their old loops in the customary manner, and are then lowered to the tucking height indicated at *D*¹, the said needles being subsequently lower to take and knit both of the threads *g* and *p*. Simultaneously, the dial needles are thrown fully outwards, as shown at *G*¹ in Figure 4, clear their old loops beneath their latches and are retracted to take the ground yarn *g* in their hooks but the plating yarn *p* under their latches. Both sets of 40 needles 1 and 2, therefore, take and knit the ground yarn and the cylinder needles 1 also knit and plate the yarn *p* but the said yarn *p* being received beneath the latches of the needles 2, is cast off the said needles 2, with the loops 45 of the last preceding course, plates the upper parts of said loops and appears on the same face of the fabric as it does when it is subsequently 50 cast off from the cylinder needles.

It has been found advantageous to position the 55 aperture 8, through which the plating yarn *p* is fed to the needles, as shown, to the rear of and below the aperture 7 through which the ground thread *g* is fed. This ensures the plating yarn being laid upon the dial needles under the latches 60 thereof and there is no tendency for the loose plating thread to move out of position and the necessity for the keeper member 5, as shown in Figures 1 and 2, is obviated.

In a machine for producing the double fabric 65 in which the ribs of one web are disposed between the ribs of the other, any desired even number of feeders may be provided, the feeders applying thread to the one set of needles alternating with the feeders supplying separate thread 70 to the other set.

Each of the two sets of needles producing the 75 improved double plated ribbed fabric may operate in exactly the same manner as the needles hereinbefore described in connection with the production of the single web fabric as hereinbe-

fore described the dial needles may be regarded as one set and the cylinder needles as the other set, each of the two sets of needles for producing the double web fabric is composed of alternate of both dial and cylinder needles.

I claim:—

1. A machine for the production of ribbed knitted fabric having two sets of needles which draw their loops in opposite directions, thread feeding means for feeding a ground and a plating thread to said needles, cams for operating the needles of one set to knit the ground and plating threads and the needles of the other set to knit the said ground thread and to receive the said plating thread over their latches and means for subsequently displacing the needles of the second set to cause the said plating thread to take up a position below the said latches to be cast off with the old loops on the said needles. 10 15

2. A machine for the production of ribbed knitted fabric having two sets of needles which draw their loops in opposite directions, thread feeding means for feeding ground and plating threads to said needles, means for operating the needles of one set to knit the ground and plating threads and the needles of the other set to knit only the ground thread, said latter needles receiving the said plating thread but casting off same with their old loops, and the needles of one set being operated to draw an equal amount 20 25 of plating and ground thread and to form loops of both threads and the needles of the other set being operated to form loops of ground thread only.

3. A machine for the production of ribbed knitted fabric having two sets of needles which draw their loops in opposite directions, thread feeding means for feeding ground and plating threads to said needles, cams for operating the needles of one set to knit the ground and plating 30 35 threads, and the needles of the other set to knit the said ground thread and to receive the said plating thread but to cast off the said plating thread with their old loops, and a keeper member positioned at the rear of the needles of the first 40 named set and beneath the needles of the second named set for assisting in retaining loose loops 45 of plating thread upon the needles of said second set and means co-acting with and operating upon the plating thread to draw loops of such threads 50 upon the needles of the second set and maintain said loops upon said needles during the projection thereof.

4. A machine for the production of ribbed knitted fabric having a set of vertically disposed 55 cylinder needles and a second set of horizontally disposed dial needles, thread feeding means for feeding ground and plating threads to said needles, the cylinder needles being operated to knit the ground and plating threads, the dial needles 60 being operated to knit the said ground thread and to receive the said plating thread with their old loops, and a keeper member positioned at the rear of the cylinder needles and beneath the dial needles adapted to retain loose loops of the plating thread upon the dial needles subsequent to the said plating thread being laid upon the said dial needles and prior to the said thread being cast off said needles with their old loops.

5. A machine for the production of a plated 70 double ribbed fabric, having two sets of latch needles which draw their loops in opposite directions, means for advancing the needles of one set to clear their old loops below the latches and for simultaneously advancing the second set to 75

a tucking position, a thread feeder for feeding a plating thread to the needles, means for moving the first set to tucking heights and for moving the second set simultaneously to draw the 5 plating thread between the needles of the first set, a keeper member positioned at the rear of the needles of the first set and beneath the needles of the second set, said keeper functioning to retain loose loops of the plating thread upon 10 the needles of the second set, means for advancing the needles of the second set to clear their old loops and the plating thread below their latches, a thread feeder for feeding a ground thread to both sets of needles, and means for then causing 15 both sets of needles to knit both threads.

6. A machine for the production of plated double ribbed fabric, having two sets of latch needles which draw their loops in opposite directions, means for moving the needles of both sets to clear 20 their loops substantially simultaneously, thread feeders for feeding a ground thread and a plating thread to the needles, means for moving the nee-

dles of one set to draw and measure an equal amount of both ground and plating thread and to form loops of both threads and for moving the needles of the other set to form loops of ground thread and to receive the plating thread beneath 5 the latches and for subsequently knitting the ground thread but casting off the plating thread with loops of a preceding course.

7. A machine for the production of ribbed knitted fabric having two sets of needles which draw their loops in opposite directions, thread feeding means for feeding a main and an auxiliary thread to said needles, cams for operating the needles of one set to knit the main and auxiliary threads and the needles of the other set to knit 10 the said main thread and to receive the said auxiliary thread over their latches and means for subsequently displacing the needles of the second set to cause the said auxiliary thread to take up a position below the said latches to be 15 cast off with the old loops on the said needles.

JOHN ARCHIBALD PHILLIPS.
